UNITED STATES PATENT OFFICE.

WILLIAM M. BRADSHAW AND WALTER G. MYLIUS, OF WILKINSBURG, PENNSYLVANIA,
ASSIGNORS TO WESTINGHOUSE ELECTRIC AND MANUFACTURING COMPANY, A COR-
PORATION OF PENNSYLVANIA.

PREPAYMENT WATT-HOUR METER.

1,274,672.

Specification of Letters Patent.

Patented Aug. 6, 1918.

Application filed November 25, 1914. Serial No. 873,924.

To all whom it may concern:

Be it known that we, WILLIAM M. BRADSHAW, a citizen of the United States, and a resident of Wilkinsburg, in the county of Allegheny and State of Pennsylvania, and WALTER G. MYLIUS, a citizen of the United States, and a resident of Wilkinsburg, in the county of Allegheny and State of Pennsylvania, have invented a new and useful Improvement in Prepayment Watt-Hour Meters, of which the following is a specification.

Our invention relates to watthour meters of the prepayment type, and it has particular reference to the coin-controlled operating mechanism of such meters.

One object of our invention is to provide a main spring that is wound from one end and is continuously released from its other end, in accordance with the power consumed.

Another object of our invention is to provide a quick-break switch that is closed when a main shaft is rotated and is controlled by the relative positions of the ends of the main spring.

Another object of our invention is to provide totalizing devices for indicating the number of coins inserted in the meter.

Another object of our invention is to so arrange the coin-controlled mechanism that it may be easily applied to the usual form of watthour meter without appreciably increasing the size of the meter.

Heretofore, watthour meters of the prepayment type have been constructed that comprised a main spring, a switch operated by the main spring and a controlling mechanism that released the main spring after the predetermined amount of energy had been consumed. While instruments of this type have operated satisfactorily, they are bulky and require a specially constructed watthour meter and complicated controlling mechanisms.

We provide a watthour meter of the prepayment type that does not require a complicated mechanism and that may be easily adapted to a watthour meter of the usual type.

In the accompanying drawings, Figure 1 is a front view, partially in elevation and partially in section, of a prepayment meter embodying our invention; Fig. 2 is a front elevational view, with parts broken away, of the meter shown in Fig. 1; Fig. 3 is a side

view, partially in elevation and partially in section, of the meter shown in Figs. 1 and 2; Figs. 4 and 5 are side and front views, respectively, of the main rotating shaft employed in our invention; Figs. 6, 7 and 8 are a top plan view, a side elevational view and a front elevational view, respectively, of a coin device that is embodied in our invention; Fig. 9 is a top view, partially in plan and partially in section, of the mechanism that is embodied in our invention; Fig. 10 is a view taken on the line X—X of Fig. 9, and Fig. 11 is a view taken on the line XI—XI of Fig. 9.

A prepayment watthour meter 1 comprises a casing 2 that supports an ordinary watt-hour meter 3, a switch 4, a coin-controlled mechanism 5, an escapement mechanism 6, a coin device 7 and a coin receptacle 8.

The watthour meter 3 comprises a magnetizable core member 9, magnetizing windings 75 (not shown), a rotatable armature 10 that is mounted upon a shaft 11 and a plurality of damping magnets 12, substantially as shown in the drawings.

The magnetizing windings are electrically connected to the stationary contact members 13 and 14 of the switch 4. The switch 4 comprises, besides the contact members 13 and 14, a rotatably mounted insulating member 15 that has a bridging contact member 16 mounted thereon, a pinion 18 and a pin 19 to which is attached one end of a spring 20, the other end of which is attached to a stationary pin 21. The member 15 and the pinion 18 are secured together and are rotatably mounted on a pin 18^a. A segmental gear wheel 22 is mounted on the end of a main shaft 24 and is adapted to engage the segmental pinion 18 for the purpose of operating the switch. The shaft 24 forms a part of the coin device 7 and has mounted thereon a pinion 25 and a hollow cylindrical member 26 having two diametrically opposite longitudinal slots 27 therein. The cylindrical member 26 is disposed in a casing 28 that has a slot 29 in its upper end. A coin device 30 is disposed within the cylindrical member 26 and is provided with a handle 31, an opening 32 for receiving a coin and a flange 32^a that engages a pin 32^b in the casing 28 where the device 30 is turned 180°. The opening in the coin device 30 is of such size that, if a coin of the correct denomination

is inserted in the slot 29, it will clamp the member 26 and the member 30 together so that, when the handle 31 is turned, the shaft 24 will also turn.

5 The coin-controlled mechanism 5 comprises a shaft 33 having a spring case 34 and a pointer 36 permanently mounted thereon and a collar 35 loosely mounted thereon. A dial 37 is mounted on the collar, and a main 10 spring 38 has its inner end attached to the collar 35 and its outer end connected to the spring case 34. The spring case 34 is provided with a gear wheel 39 that engages a pinion 40, for reasons hereinafter more fully 15 set forth. A gear wheel 41 is also mounted on the collar 35 and to engage an idler gear wheel 42 which also engages the pinion 25 on the shaft 24. A ratchet wheel 43 is mounted on a shaft 44, with the idler gear 20 wheel 42, and is engaged by a restraining pawl 45 to prevent the unwinding of the spring 38 from its inner end.

The shaft 11, upon which is mounted the armature 10, is provided with a pinion 46 25 that engages a gear wheel 47. The gear wheel 47 is mounted on a shaft 48 that also has a worm screw 49 mounted thereon. The worm screw 49 engages a worm wheel 50 that is mounted on a shaft 51, with an eccentric 30 strap 53. An eccentric strap 53 is mounted on a shaft 54 to engage the eccentric 52, substantially as shown. A double pallet 55, that is also mounted on the shaft 54, engages an escapement wheel 56 that is mounted on 35 a shaft 57, with a pinion 58. The pinion 58 engages a gear wheel 59 that is mounted on a shaft 60, with the pinion 40.

Upon two projections 61 of the spring case 34, is pivotally mounted a shaft 62 that 40 has two arms 63 and 64 attached thereto. The arms 63 and 64 are substantially at right angles to each other and the former extends through an opening 65 in the spring case 34 for the purpose of engaging an arm 45 66 that is attached to the collar 35. The arm 63 engages the arm 66 when the spring is unwound a predetermined degree, and the engagement of the two arms causes the shaft 62 to turn and the arm 64 to engage a bell 50 crank lever 67 that has a circular portion 68 disposed around the shaft 33 and a straight portion 69 that engages the pin 72 in the movable member of the switch 4. A disk 70 is mounted upon the collar 35 and is provided 55 with a notch 71 and a pin 72. A gear wheel 73 is adapted to engage the disk 70 and be actuated by the pin 72 every time the disk 70 rotates one revolution. The gear wheel 73 is provided with a scale 74 that is 60 visible through an opening 75 in the front of the casing 72. The scale 74 is for the purpose of assisting in indicating the number of coins that have been inserted in the coin receptacle 8. A stationary scale 74^a is provided 65 to coöperate with the scale 74 to indi-

cate the number of coins inserted in the receptacle 8.

Assuming that the switch 4 is open and that it is desired to supply energy to a circuit, our invention operates as follows: 70

A coin is inserted in the slots 29, 27 and 32 and the handle 31 is turned 180° to allow the coin to drop into the receptacle 8. Further rotation is prevented by reason of the engagement of the flange 32^a and the pin 75 32^b. Since, when the switch 4 is in its open position, the segmental gear wheel 22 and the segmental pinion 18 are engaged, the turning of the handle 31 will rotate the segmental gear wheel 22 which causes the gear 80 wheel 18 and the insulating member 15 to turn in a counter-clockwise direction until the portions of the gear wheel 22 and the pinion 18 that are not provided with teeth become disengaged from each other. The 85 spring 20 will then cause the member 15 to turn further in a counter-clockwise direction and the contact member 16 to engage the stationary contact members 13 and 14 with a quick action. The pin 17 engages the arm 90 69 of the bell crank lever 67 and restrains the switch 4 in its closed position as shown in Figs. 10 and 11. The turning of the handle 31 causes the pinion 25 to drive the idler gear wheel 42 and this drives the gear wheel 95 41 that is mounted on the collar 35. The turning movement of the collar 35 winds the spring 38 from its inner end and also causes the dial 37 to be turned a predetermined distance. The turning of the dial 100 causes the pin 72 to engage the gear wheel 73 once each revolution, as hereinbefore described. Since the arm 66 is mounted upon the sleeve 35, it is also turned a predetermined distance every time the handle 31 is 105 turned 180°.

After the switch 4 is closed, the armature 10 will rotate if current traverses the windings of the instrument. The rotation of the armature causes the eccentric 52 to be rotated through the shaft 51, worm wheel 50, worm screw 59, shaft 48, gear wheel 47 and pinion 46. The rotation of the eccentric 52 causes the shaft 54 to be oscillated and this actuates a double pallet 55 to release the 110 escapement wheel 56, in accordance with the amount of energy being metered or in accordance with the speed of the armature 10. Since the outer end of the spring 38 is connected to the spring case 34, and since the 115 spring case 34 is operatively connected to the pinion 40, that is mounted on the shaft 60 with the gear wheel 59, the spring 38 will be continuously unwound from its outer end in accordance with the 120 speed of the armature 10. The spring case 34 rotates, as released, in the same direction that the collar 35 is turned when the spring 125 is being wound. Thus, when the lever 66 is being wound, the lever 64 is caused 130

- to engage the circular portion 68 of the bell crank lever 67 to disengage the arm 69 from the pin 17. The disengagement of the arm 69 from the pin 17 causes the spring 20 to 5 quickly turn the member 15 in a counter-clockwise direction from the position shown in Figs. 10 and 11 to disengage the contact member 16 from the contact members 13 and 14. The spring 20 is adapted to bias the 10 member 15 toward either side of its dead-center position.

- Since the dial 37 is rotated a predetermined distance every time the shaft 24 is turned 180°, the distance moved by the dial 15 will indicate the number of coins that have been inserted in the instrument and, since the dial 37 moves in the same direction as the dial, the position of the pointer, at any instant, will indicate the number of coins to 20 the customer's credit in the instrument, and the pointer 36, in coöperation with the stationary dial 74^a, will indicate the number of coins in the receptacle in conjunction with the dial 74. 25 It will be understood that, when the pointer 36 coincides with the zero marking of the dial, irrespective of the position that the zero marking has assumed, that the switch 4 will be opened and the armature 30 will cease rotating.

- In order to maintain a check on the instrument reader, the gear wheel 73 and the dial 74^a have been provided. These are read each time the receptacle 8 is emptied, and 35 the difference in the successive readings should correspond to the number of coins in the receptacle 8.

- Our invention is not limited to the particular construction illustrated but may be 40 variously modified within the scope of the appended claims.

We claim as our invention:

1. A meter comprising a rotatable armature, a main spring adapted to be wound 45 from one end, means controlled by the rotation of the armature for permitting the spring to unwind continuously from the other end, a switch, and means actuated by both ends of the spring for tripping the 50 switch.

2. A meter comprising a rotatable armature, a main spring adapted to be wound from one end, means controlled by the rotation of the armature for permitting the spring to 55 unwind continuously from the other end, a switch biased toward its open position, means for holding the switch in its closed position, and means actuated by the coöperation of both ends of the spring for actuating the switch-holding means to trip the switch.

3. In a prepayment watthour meter, the combination with a main shaft and a main spring, of a segmental gear wheel mounted 65 on the main shaft, a pivotally mounted

member having a contact member and a segmental pinion mounted thereon, said pinion being adapted to engage the segmental gear wheel, means for biasing the pivotally mounted member on each side of its dead-center position, means for holding the pivotally mounted member in a predetermined position, and means controlled by the relative position of the ends of the main spring for controlling the said holding means. 70 75

4. In a prepayment meter, the combination with a coin-controlled shaft, of a segmental gear wheel mounted on the shaft, a pivotally-mounted member having a contact member and a segmental pinion mounted 80 thereon, said pinion being adapted to engage said gear wheel when the shaft is turned under predetermined conditions, means for actuating the pivotally mounted member independently of the shaft after the shaft 85 is turned a predetermined distance, and means for retaining the pivotally mounted member in a predetermined position.

5. In a meter, the combination with a rotatable member, of a switch, a main spring 90 that is wound from one end, an escapement mechanism that is operated by the said rotatable member for permitting the unwinding of the main spring from its other end, and means controlled by the relative positions of the two ends of the said main spring 95 for tripping the said switch under predetermined conditions.

6. In a prepayment meter, the combination with a coin-controlled shaft, of a pivotally mounted contact-carrying member, means whereby the turning of the shaft moves the contact-carrying member to a predetermined position, and means for independently moving the contact-carrying 100 member into another position, irrespective of further movement of the shaft.

7. A meter comprising a rotatable member, a main spring having a pointer connected to one end thereof and a dial to the 110 other end thereof, an escapement mechanism operated by the said rotatable member for permitting the said spring to unwind from one end to cause the said pointer to rotate in the same direction as the said dial, and 115 means depending upon the relative positions of the pointer and the said dial for controlling the operation of the said meter.

8. In a meter, the combination with a rotatable member, of a main shaft, a switch 120 operatively connected to the said main shaft, a main spring that is wound from one end by the rotation of the said main shaft, an escapement mechanism that is operated by the said rotatable member for permitting the 125 unwinding of the main spring from its other end, and means controlled by the relative positions of the two ends of the said main spring for tripping the said switch.

9. In a prepayment meter, the combina- 130

- tion with a coin-controlled shaft, of a pivotally mounted contact-carrying member, means whereby the turning of the shaft moves the contact-carrying member to a predetermined position, and a spring for independently snapping the contact-carrying member into another position, irrespective of further movement of the shaft.
10. In a prepayment meter, the combination with a coin-controlled shaft, of a rotatable contact-carrying member, means for operatively connecting the shaft to the rotatable member, under predetermined conditions, whereby the turning of the shaft moves the rotatable member to a predetermined position, and means independent of the shaft for moving the rotatable member to another predetermined position after it is disconnected from the shaft.
20. 11. In a prepayment watthour meter, the combination with a main shaft and a main spring, of a segmental gear wheel mounted on the said main shaft, a pivotally mounted member having a contact member and a segmental pinion mounted thereon, said pinion being adapted to engage the said segmental gear wheel, a resilient member attached, at one end, to the said pivotally mounted member and at its other end to the frame of the said meter, and means controlled by the said main spring for restraining the said pivotally mounted member in a predetermined position.
12. A prepayment meter comprising a rotatable dial adapted to be moved a distance proportional to the amount of money inserted in the meter, a pointer adapted to move in the same direction as the dial to cooperate therewith to indicate the remaining energy to the customer's credit, a second rotatable dial adapted to move a predetermined amount for each rotation of the first dial and a stationary scale adapted to cooperate with the said dials to indicate the total number of coins in the meter.
30. 13. A prepayment meter comprising a rotatable armature, a main spring having a pointer connected to one end thereof and a dial to the other end thereof, an electric switch for controlling the circuit of the said meter, an escapement mechanism operated by the said armature for permitting the said spring to unwind continuously from its outer end to cause the said pointer to rotate in the same direction as the said dial, and means depending upon the relative positions of the pointer and the said dial for tripping the said switch.
40. 14. In a prepayment watthour meter, the combination with a rotatable armature, of a spring that is wound from one end and unwound from its other end, a main shaft having a segmental gear wheel mounted thereon, a pivotally mounted member having a segmental pinion and a bridging contact member mounted thereon, said segmental pinion being adapted to engage the said gear wheel when the said member is rotated, means for tending to move the said pivotally mounted member to a predetermined position, stationary contact members for coöoperating with the bridging contact member, and means controlled by the relation of the two ends of the spring for restraining the said contact members in their closed positions.
50. 15. A prepayment meter comprising a rotatable dial adapted to be moved a distance proportional to the amount of money inserted in the meter, a pointer adapted to move in the same direction as the dial to coöperate therewith to indicate the remaining energy to the customer's credit and means to coöperate with the dial to indicate the total number of coins inserted in the meter.
60. 16. In a prepayment watthour meter, the combination with a coin-controlled shaft, of a segmental gear wheel mounted on the shaft, a pivotally-mounted member having a contact member and a segmental pinion mounted thereon, said pinion being adapted to engage the said gear wheel under predetermined conditions, means for biasing the pivotally-mounted member into two positions, and means for retaining the said pivotally-mounted member in a predetermined position.
70. 17. In a prepayment watthour meter, the combination with a coin-controlled shaft, of a segmental gear wheel mounted on the shaft, a pivotally-mounted member having a contact member and a segmental pinion mounted thereon, said pinion being adapted to engage the said gear wheel under predetermined conditions, means for biasing the pivotally-mounted member into two positions, a stationary contact member, and means for restraining the contact members in engagement under predetermined conditions.
80. In testimony whereof, we have hereunto subscribed our names this 20th day of Nov., 1914.
